[57] CLAIM

The ornamental design for a carrying case, as shown and described.

DESCRIPTION

FIG. 1 is a front elevational view of a carrying case showing my new design;

FIG. 2 is a top plan view thereof;

FIG. 3 is a bottom plan view thereof;

FIG. 4 is a left side elevational view thereof;

FIG. 5 is a right side elevational view thereof;

FIG. 6 is a rear elevational view thereof; and,

FIG. 7 is a front elevational view of a second embodiment of FIG. 1, the only difference residing in the dual watch element.
